UNITED STATES PATENT OFFICE.

CHARLES E. BOURNE, OF BOSTON, MASSACHUSETTS, ASSIGNOR OF ONE-HALF
TO WILLIAM BOURNE, OF SAME PLACE.

FALL-BOARD FOR UPRIGHT PIANOS.

SPECIFICATION forming part of Letters Patent No. 247,473, dated September 27, 1881

Application filed July 28, 1880. (No model.)

To all whom it may concern:

Be it known that I, CHARLES E. BOURNE, of Boston, Massachusetts, have invented an Improvement in Fall-Boards for Upright Pianos, of which the following is a specification.

The object of my invention is to so construct the fall-board of an upright piano that it may be thrown back in opening the instrument without interfering with the music-rack, and also to so connect it with the music-rack that the latter will be put in position automatically by the opening of the instrument.

In the accompanying drawings, Figure 1 is a side view of an upright piano containing my invention, showing the position of the parts when closed. Fig. 2 is a similar view of the instrument on a larger scale, showing the position of the parts when open, the dotted lines also indicating their position when closed. Fig. 3 shows one of the arms to which the front portion of the fall-board is attached. Fig. 4 is a front view of the instrument, showing the position of one of these arms at the side of the fall-board.

The fall-board is made in two parts, A and B, united by hinges opening upward. The front portion, A, is attached to the case of the piano by two arms, C C, one on each side, fastened rigidly at the upper ends to the sides of the fall-board, and pivoted by means of open slots at the lower ends to studs or pins in the case of the instrument. The rear end of the part B is also attached to the case above it by arms D D, hinged at each end, so as to permit it to swing freely backward and downward

when the fall-board is thrown back in opening the instrument.

Behind and above the fall-board, and pivoted to the case of the instrument, is the curved lever E, whose lower end is in contact with the back side of the fall-board B, while the upper end rests against the back side of the music-rack F, which is suspended by hinges at its upper edge in the usual manner.

Attached to the music rack is a spring, G, 45 the other end of which is fastened to the piano-case, so as to aid in bringing the music-rack back to a perpendicular position when the pressure of the lever E is withdrawn.

The construction and arrangement of the 50 parts are such that when the fall-board A is raised and thrown back in opening the instrument the part B is carried backward and downward within the case, allowing the part A to be turned up under the music-rack without interfering with it. At the same time the pressure of the part B upon the lever E throws the lower end of the music-rack outward into place.

What I claim, and desire to secure by Letters Patent, is—

1. The jointed fall-board A B, suspended by the arms C C D D, substantially as and for the purpose described.

2. The fall-board A B, lever E, and music-rack F, combined and arranged substantially 65 as and for the purpose described.

CHARLES E. BOURNE.
